UNITED STATES PATENT OFFICE.

EDWARD E. WAKEFIELD, OF PROVIDENCE, RHODE ISLAND, ASSIGNOR TO HALKYARD MANUFACTURING COMPANY, OF PROVIDENCE, RHODE ISLAND, A CORPORATION OF RHODE ISLAND.

LACING-STUD-SETTING MACHINE.

1,154,553.

Specification of Letters Patent. Patented Sept. 21, 1915.

Application filed September 24, 1914. Serial No. 863,250.

To all whom it may concern:

Be it known that I, EDWARD E. WAKEFIELD, a citizen of the United States, and resident of the city of Providence, in the county of 5 Providence and State of Rhode Island, have invented certain new and useful Improvements in Lacing-Stud-Setting Machines, of which the following is a specification.

This invention relates to improvements in 10 machines for automatically setting lacing studs such as hooks or eyelets in shoe uppers, and is of the class adapted to feed a strip of reinforcing tape to be connected to the shoe upper by the setting of lacing studs 15 thereinto, and also in which means are provided for severing the tape into predetermined lengths, and the object of my present invention is to provide means for automatically adjusting the cutting members 20 relative to each other to compensate for wear on said members.

This invention is an improvement on my co-pending application Serial No. 845,939.

It is found in practice that where the 25 strip of tape is fed to the machine and cut and severed at predetermined intervals that unless the tape is completely severed at each cutting operation the unsevered threads hold the parts together and prevent the proper 30 placing and positioning of the partially severed pieces onto the upper, and it is also found that the reason for such imperfect work is due largely to the wearing of the cutting surfaces of the shearing plates. To 35 obviate this difficulty and insure a complete severing of the tape at each cutting operation, I have provided simple and effective means in the operating parts to automatically compensate for this wearing to keep 40 the cutter plates always in proper working relation with each other.

With these and other objects in view, the 45 invention consists of certain novel features of construction, as will be more fully described, and particularly pointed out in the appended claims.

In the accompanying drawings: Figure 1— is a side elevation illustrating a portion 50 of the mechanism for feeding the shoe upper, means for feeding the reinforcing tape, and means for severing the same into predetermined lengths, to which mechanism is attached my improved automatic adjustment for the severing plates. Fig. 2— is 55 a plan view of a portion of the mechanism

showing means in the presser foot block for adjusting the relative position of the cutter plates. Fig. 3— is a side elevation showing the means for setting the presser foot also showing the block slidably mounted in 60 said presser foot. Fig. 4— is an enlarged sectional view showing means for automatically adjusting the cutter plates relative to each other. Fig. 5— is a view of the inner side of a shoe upper showing the tape as 65 having been positioned to serve as a backing or reinforcement for the studs when riveted thereto. Fig. 6— is a greatly enlarged edge view of the work showing the lacing studs in the form of hooks and eyelets as set into 70 a shoe upper and my reinforcing tape in position to serve as a support or backing for the studs riveted in position in the work.

In my co-pending application above referred to I have described and shown the 75 mechanism to which my present improved mechanism is attached and by which it is operated. I have also set forth the fact that the term "lacing stud" used throughout the 80 specification and claims, refers to and includes both the eyelet and lacing hook formation ordinarily employed in shoe uppers, and the same is intended to apply with equal 85 force to my present patent application. I have herein shown and described only sufficient mechanism to illustrate my present invention.

In the accompanying drawings 10 designates a portion of the carriage in which is mounted the punch spindle 11 and the spring 90 pressed presser foot spindle 12, the latter spindle being supported from the former by the collars or guide blocks 13 and 14. To this spindle 11 is connected the punch 15 which forms holes in the tape 16 for the reception 95 of the lacing studs 17, also on this spindle is mounted the cutter 26 for severing the reinforcing tape. The guide block 14 connected to the spindle 11 also serves to carry one or more needles or spurs 19, which are arranged to engage the tape for the purpose of causing it to advance with the feeding movement of the carriage head, which is fully described in my above mentioned patent application. The usual presser foot 20 which 100 is raised and lowered through the rod 21 by means (not shown) is provided with ways 22 in which slides the block 23. This block is slotted at 24 longitudinally to receive the tape 16 which passes therethrough 105 110

and the forward face of this block is provided with a cutter plate 25 against which works the second vertically reciprocable cutter plate 26 carried by the punch spindle 11. 5 This block is also provided with vertical holes 27 through which needles 19 pass on their way into and out of engagement with the reinforcing tape.

The essential feature of my improved invention is the provision of means for permitting an adjustment of the cutter plates relative to each other so as to compensate for wear between them. One means for simply and practically accomplishing this 10 purpose is herein shown and illustrated, which is that of cutting away or removing the middle portion of the upper face of this block 23 into which recessed portion is slidably mounted a socket plate 28 connected rigidly to the end of spindle 12. One 15 end of this plate extends out over the rear end of the block and is provided with a downwardly extending finger 29 through which a screw 30 is passed and threaded into the rear wall of said block and between the 20 block and the flange is inserted a tension spring 31 which exerts a forward pressure upon the block to maintain its front cutter plate 25 always in contact or in operative 25 relation to the reciprocating cutter plate 26 so as to take up or to compensate for any 30 wear of these plates and to keep the cutters in operative relation to produce effective 35 work and sever the tape at each downward stroke of the punch spindle.

The tape 16 is led from the reel (not shown) through a suitable guide 35 supported from the arm 36 in which guide a tension spring 37 is mounted to prevent the 40 tape from receding or moving backward during the return stroke of the feeding mechanism. From this guide the tape is led through the aperture 24 in the guide block 23 above the engaging surface of the presser foot and over the cutting edge of the cutter 45 plate 25. When the punch spindle descends it carries with it the knife plate 26 which slides down across the face of the cutter plate 25 and severs the portions 34 of the 50 tape which extends through the block 23. The downward movement of this spindle 11 also causes the punch 15 to engage and carry the severed portions of the tape down against the shoe upper or work "b" and to 55 punch a hole through the tape and also through the work to receive the stud. The work is next advanced bringing the punched holes into position to receive the stud which is passed through said holes in both the 60 upper and tape and riveted in position over the piece of tape as fully described in said co-pending application. After the stud has been set the spindle 11 is raised, withdrawing the spurs 19 and knife plate 26 from engagement with the tape and the head is then 65

carried to the right back into position illustrated in Fig. 1 and this cycle of operations is repeated in the setting of each stud into the work.

I have shown and described one form of mechanism for automatically compensating for the wear of the cutting members, but any means which may be used in conjunction with the feeding and cutting the tape and connecting the same to the shoe upper for accomplishing the automatic adjustment of the cutting members will fall within the spirit and scope of my invention.

I claim:

1. In a machine for applying studs to shoe uppers, means for feeding an upper, means for feeding a reinforcing strip a distance substantially equal to the feeding movement of the upper, a cutter member mounted to move with said strip feeding means, a second coöperating cutter member, and means for automatically adjusting said cutter members relative to each other.

2. In a machine for applying studs to shoe uppers, a plunger for feeding the shoe upper, means for feeding a reinforcing strip a distance substantially equal to the feeding movement of the upper, a cutter member mounted to move with said strip feeding plunger, a second coöperating cutter member, means for applying studs and severed sections of said strip to the upper and means for automatically adjusting said cutter members relative to each other.

3. In a machine for applying studs to shoe uppers, means for feeding an upper, means for feeding a reinforcing strip a distance substantially equal to the feeding movement of the upper, a cutter member mounted to move vertically with said strip feeding means, a second coöperating cutter member held against vertical movement, and spring actuated means for automatically adjusting said cutter members relative to each other to compensate for wear.

4. In a machine of the class described the combination with means for setting lacing studs, of a presser foot for holding the work while being operated upon, a presser foot spindle, a member actuated by said spindle in said presser foot, a cutter plate in said member through which the tape is fed, a second cutter plate coöperating with said first plate to sever the tape into predetermined lengths and means for adjusting said plates relative to each other.

5. In a machine of the class described the combination with means for setting lacing studs, of a presser foot for holding the work while being operated upon, a presser foot spindle, a member actuated by said spindle to slide in said presser foot, a cutter plate in said member through which the tape is fed, a second cutter plate coöperating with said first plate to sever the tape into prede-

termined lengths, and spring actuated means for automatically adjusting said plates relative to each other to compensate for wear of said plate.

- 5 6. In a machine of the class described the combination, with means for setting lacing studs, of a presser foot spindle, a presser foot, a member actuated by said spindle to slide on said presser foot, means for feeding the reinforcing tape, a cutter plate on said member over which the tape is led, a

second cutter plate coöperating with the first plate to sever the tape into predetermined lengths, and means carried by the presser foot spindle for causing the wear of said cutter plate to be automatically taken up. 15

In testimony whereof I affix my signature in presence of two witnesses.

EDWARD E. WAKEFIELD.
